UNITED STATES PATENT OFFICE.

DAVID S. WILLIAMS, OF PHILADELPHIA, PENNSYLVANIA, ASSIGNOR TO HIMSELF AND JOSEPH A. VINCENT, OF SAME PLACE.

PETROLEUM INCANDESCENT LAMP.

SPECIFICATION forming part of Letters Patent No. 634,125, dated October 3, 1899.

Application filed November 2, 1898. Serial No. 695,278. (No model.)

To all whom it may concern:

Be it known that I, DAVID S. WILLIAMS, a citizen of the United States of America, and a resident of Philadelphia, in the county of Philadelphia, State of Pennsylvania, have invented certain new and useful Improvements in Petroleum - Oil Incandescent Lamps, of which the following is a specification.

My invention relates to improvements in devices for producing heat and light from petroleum oil, and is especially designed for, although not necessarily confined to, the use of oil having a specific gravity of about .807, a flashing-point of upward of 110° Fahrenheit, and a burning-point of upward of 125° Fahrenheit.

My invention consists of an improved vaporizer consisting of a plurality of retorts corresponding in number to the burners and arranged respectively directly above the same. In the construction I have shown each retort, except the last of the series, has a branch or projection of smaller diameter than and extending into and through the next vaporizer of the series, whereby I secure a large heating area within a comparatively short length of vaporizer and effect a thorough superheating of the vapor prior to mixing it with air.

The invention also consists in a particular arrangement of the expansion-tube and burner with respect to the vaporizer.

It also consists in a construction and arrangement of the air-passages leading to the expansion and mixing tube for overcoming the noise common to burners of the type referred to.

It also consists of an arrangement of pipe connections between the oil-reservoir and the lamps whereby compressed air may be forced through the vaporizer for the purpose of removing deposits of carbon therein.

It also consists in various details of construction, which will be fully dealt with hereinafter.

Referring to the accompanying drawings, Figure 1 illustrates a diagrammatic view of the oil-supply reservoir and the burners or lamps communicating therewith by a line of pipe. Fig. 2 illustrates a perspective view of the

preferred form of my burner, which may be employed for the purpose of creating light energy by the use of a mantle of refractory material. Fig. 3 represents a plan view of

the same. Fig. 4 illustrates a perspective view of a burner, the retort of which is arranged to vaporize oil for a three-burner-head cluster. Fig. 5 illustrates a plan view of Fig. 4 with the vaporizing-retort in section. Fig. 6 represents a detached vertical section of the vaporizer shown in Figs. 2 and 3. Fig. 7 illustrates a plan view of the hood and connections employed in conjunction with the burners shown in Figs. 2 and 4. Fig. 8 represents a vertical section of the hood with the burner attached, the burner being provided with incandescent mantles and surrounded by a transparent globe. Fig. 9 illustrates a horizontal section of hood on the line 9 9 of Fig. 8, showing the manner in which air is admitted through the hood to the mixing-chamber. Fig. 10 represents a vertical section of the hood and burner, taken on line 10 10 of Fig. 8, looking in the direction of the arrow. Fig. 11 illustrates a vertical section of the spring-actuated check-valve which is designed to be placed upon the supply-pipe on each of the lamps, and Fig. 12 represents a vertical section of a diaphragm-valve designed to be placed upon each of the burners for the purpose of completely cutting off the supply of oil when the same are not in use.

Referring to the letters of reference upon the drawings, A represents a reservoir into which the oil is placed and maintained under a considerable pressure by the use of a small pump a', which is so arranged that either air or oil may be forced into the reservoir when desired. The pump a' is secured to the lower portion A' of the reservoir, into which the oil is placed prior to being forced into the portion A, the pump having a connection a², provided with a check-valve a³, and a strainer a⁴. All of said parts are arranged within the portion A' of said reservoir. Above the portion A' of the reservoir is a connection a⁵, which leads from said pump to the upper or pressure portion of the reservoir, the same being provided with a check-valve a⁶, and on the opposite side of reservoir is an opening a⁷, through which oil is admitted and which is kept normally closed by means of a spring-seated valve a⁸.

Within the reservoir A is a float a⁹, to which is secured a tape a¹⁰, having marked upon it figures which indicate the number of gallons of oil in the reservoir, which may be seen at

a glance through the glass-covered sight a^{11} in the top of the reservoir. The tape a^{10} is wound upon a spool a^{12} by means of a spring a^{13} , which takes up the slack tape as the oil 5 enters the reservoir and raises the float.

a^{14} is a pressure-gage to record the pressure in the tank.

a^{15} is the oil-supply pipe, which conveys the oil to the lamps L. This pipe is provided 10 with a diaphragm-valve a^{16} , which is so constructed as to completely cut off the supply of oil to the lamps when desired.

a^{17} is a connection leading from the pipe 15 a^{15} to the upper end of the reservoir A and is provided with a diaphragm or other valve a^{18} .

It frequently becomes necessary in extending the supply-pipe a^{15} in making repairs, &c., to remove the oil from the supply-pipe, and for this purpose I employ a connection a^{19} 20 and valve a^{20} , by which means the oil may pass from the supply-pipe to the lower part 25 A' of the reservoir.

I have described above a simple system of supplying and regulating the supply of oil to 25 burners or lamps employed to light stores, factories, &c.; but where a large number of lamps is required the hand-pump a' can be dispensed with and a ram employed controlled by water-pressure, such as is at present used 30 in maintaining a pressure on beer and other liquors in saloons and public places.

The lamp or burner embodied in my invention is especially adapted to a construction in which two or more burner-heads are employed, and the construction of the vaporizer 35 is such that the oil or vapor therefrom will be conveyed from one to another of the retorts comprising the vaporizer until the required heat is taken up by the fluid to produce, when mixed with air, a perfect reducing-flame.

Referring to Figs. 2, 3, 4, 5, and 6 of the drawings, B represents the vaporizer, which is divided into as many retorts as there are 45 burner-heads.

In Figs. 2 and 3 the vaporizer is divided into two retorts B' and B², the retort B' being connected with an oil-supply pipe a^{15} through the medium of a coupling b' , threaded thereto.

50 The opposite end of the retort B' is reduced and passes through the retort B², the two being threaded together near the center. The retort B² is provided with a discharge-opening b^2 , which has a detachable nipple b^3 . Below the vaporizer is a mixing-chamber C, which has at its upper end air-inlet tubes C' and C² and at the bottom branches C³ and C⁴, communicating with the burner-heads C⁵ and C⁶, provided with nickel wire-gauze c⁵ and c⁶

60 and binding-posts c⁷ and c⁸ for clamping the supports for holding incandescent mantels. Extending through the mixing-chamber C is a stem D, provided with a needle d, which enters the nipple b³ and serves to regulate the 65 flow of vapor from the vaporizer. The vaporizer is arranged in such a manner that the retorts B' and B² pass directly over the burner-

heads, and is detachably secured to the mixing-tube by a set-screw c⁹. Threaded to the bottom of the mixing-chamber is a nut c¹⁰, 70 which is internally threaded to receive the stem D, and upon said nut is fastened a cup E, into which is placed a small quantity of alcohol for the purpose of heating and causing the initial vaporization of oil in the vaporizer. 75

In the construction illustrated in Figs. 4 and 5 the vaporizer B is composed of three retorts and the mixing-chamber is provided with three burner-heads. Otherwise it will 80 be seen that the construction is throughout the same, and like letters of reference are used to designate like parts. The vaporizer B has a retort B', which is provided with a coupling b' and supply-pipe a¹⁵. Leading 85 therefrom is a passage b⁴, which leads into a pipe b⁵, which is within the retort B², and practically forms an extension of the retort B', as illustrated in Figs. 2, 3, and 4. From the retort B² of the three-burner type is a passage 90 b⁶, which leads into the pipe b⁷ within the retort B³, and from the retort B³ leads a passage b⁸, which communicates with the opening b⁹ of the discharge.

It is also necessary to drain the pipe a^{15} previous to decarbonizing the vaporizing-retorts. In any petroleum-oil lamp of the character of that to which this invention relates the vaporizing-retorts become in the course of time clogged with carbon that is constantly deposited during the burning of the lamp. Various expedients have been devised to remove this deposit of carbon—in other words, to "decarbonize" the vaporizer. The construction that I have described affords a readily-manipulated means of effecting this result by means of an air-blast. In the first place it will be understood that by the manipulation of the pump a' the oil is pumped from the lower part of the upper part of the reservoir 100 A. When the oil in the lower tank sinks below the level of the strainer a⁴, by a continued operation of the pump air is forced into the upper tank until the desired working pressure is secured therein, the air in the lower tank being replenished through the valve a⁸. If it is desired to force a blast of air through 105 the vaporizer, (valves a¹⁶ and a¹⁸ being closed,) the valve a²⁰ is opened, draining the oil in pipe a¹⁵ into the lower tank. This valve is 110 then closed. Valve a¹⁷ is then opened, whereupon the compressed air in the upper tank of the reservoir rushes through pipe a¹⁵, causing a blast of air to pass through the vaporizer, removing the carbon that has been deposited 115 therein. Valve a¹⁷ is then closed. This means of clearing out the vaporizer is extremely simple and altogether inexpensive. It should be understood that the air-blast must be applied to the vaporizer while the latter is in a 120 highly-heated condition, in which case the air will combine with the carbon, producing carbon dioxid, which will be forced into and through the expansion-tube and burners. 125

The burner-heads C⁷, C⁸, and C⁹, connected to the expansion and mixing chamber C by branches c¹¹, c¹², and c¹³, are arranged directly below the retorts B', B², and B³ and have 5 binding-posts c¹⁴, c¹⁵, and c¹⁶ for supporting mantles.

In Figs. 7, 8, 9, and 10 I have illustrated the burner, which is provided with a hood F and chimney F', and below the hood I have 10 shown a glass globe G, which incloses the burner from the bottom, the whole forming a complete lamp. The air-inlet tubes C' and C² are secured to the hood F by means of nuts f and f', and above the hood is arranged a 15 curved collar F³, which surrounds the central portion F² of the hood and forms an annular chamber F⁴, which has openings f⁴ and f⁵, through which air passes to the inlet-tubes C' and C². The object of the above-mentioned 20 chamber and the arrangement of the air-passages therein is to break up the sound-vibrations caused by the induction of air into the mixing-chamber, which emits a very annoying sound peculiar to lamps of this type. 25 Above the chamber F⁴ is the chimney F', which has a flaring base F⁵, supported above the hood by means of supports f⁶, thus leaving an annular space between the flaring base F⁵ and the central portion F² of the hood, 30 through which air is induced by the products of combustion passing upward through the chimney and reduces the temperature of the hood and chimney of the lamp. Over the chimney F' is placed a cap F⁶, united thereto by a brace F⁷, and between the cap and chimney is placed a ring F⁸, formed of wire-gauze, 35 which serves to prevent the flame from passing out through the top of chimney should the lamp be badly adjusted in starting. The 40 lamp is supported from above by a rod F⁹, surrounded by a casing F¹⁰, which is of sufficient diameter to inclose the oil-supply pipe a¹⁵.

One of the chief annoyances if not a source of danger in these lamps is caused by the oxidizing or burning out of the vaporizer, which 45 cannot be avoided except the same be made of platinum or some other rare and non-oxidizable metal, the cost of which would preclude the general adaptation of the lamp. 50 Where a system of lamps is carefully attended by a skilled operator, this would not occur, as the retorts when badly oxidized could be readily removed and new ones replaced; but it too often happens that devices of this kind 55 are handled by unskilled persons and carelessly manipulated. I have succeeded in entirely overcoming any danger which might result from this cause by placing in that portion of the supply-pipe adjacent to the lamp 60 a spring-actuated check-valve H, the spring S of which is adjusted so as to keep the valve h in an elevated or balanced position when the lamp is working under normal conditions; but should the pressure be suddenly relieved 65 by a break in the vaporizing or from any other disarrangement of the working parts of the lamp and the pressure be suddenly relieved

on the burner end of the oil-supply pipe the valve would close and be firmly held upon its seat, thus completely cutting off the supply 70 of oil to the lamp.

The initial vaporization of the oil in the retorts is caused by igniting a small quantity of alcohol in the cup E, and I find it desirable in producing this initial vaporization to place 75 above the vaporizer a baffle-plate I, which is suspended from a bracket I' by a rod i and curved, so as to concentrate the heat upon the vaporizer. The outer ends of the baffle-plate are curved inwardly, so as to form a support 80 for a strip of asbestos or other refractory material, which is best adapted to receive and concentrate the heat upon the vaporizer. For street lighting and other outside use the cup may be dispensed with and a torch employed 85 to heat the retorts in producing the initial vaporization.

Another important detail of construction in a completed lamp is the valve K, which is of the diaphragm type and serves to cut off the 90 oil-supply to the lamps when the same are not in use. This valve is secured to the hood by a plate L' and placed in the supply-pipe 15^a, between the check-valve H and the vaporizer B. 95

It will be understood that while I have shown and described many desirable details of construction many changes may be made in the details herein enumerated without departing from the scope of my invention. 100

Having fully described my invention, what I claim, and desire to secure by Letters Patent, is—

1. A vaporizer for hydrocarbon-oil burners comprising a series of two or more retorts communicating with each other each of which except the last of the series has a branch extending into the next retort in the series the last retort of the series being provided with a discharge-orifice arranged centrally between the 110 group, substantially as specified. 105

2. A hydrocarbon-oil burner comprising a mixing-chamber having air-inlet tubes, a series of burners arranged about the mixing-chamber and communicating therewith, a 115 vaporizer communicating with an oil-supply pipe and having a series of two or more retorts communicating with each other and corresponding in number with the burner-heads, each of the retorts being arranged directly 120 above its corresponding burner of the series of burners, the last retort of the series being provided with a discharge-orifice opening into the mixing-chamber. 120

3. A hydrocarbon-oil burner comprising a 125 vaporizer located within the heat zone having a series of two or more detachable retorts communicating with each other, one of said retorts being provided with an oil-supply pipe, while the last in the series has a vapor-discharge orifice, a centrally-located mixing-chamber provided with air-inlet tubes, a series of burner-heads corresponding in number with the retorts and arranged about the 130

mixing-chamber and communicating therewith, each burner of said series being arranged directly below its corresponding retort.

4. A hydrocarbon-oil burner comprising a detachable vaporizer located within the heat zone having an oil-supply pipe and a vapor-discharge orifice said vaporizer having a series of two or more detachable retorts communicating with each other a centrally-located mixing-chamber communicating with the vaporizer and having air-inlet tubes, a series of burner-heads corresponding in number with the retorts and communicating with the mixing-chamber each burner of the series being located directly below its corresponding retort.

5. A vaporizer for hydrocarbon-oil burners comprising a series of two or more retorts communicating with each other which are detachably secured together, one of the retorts being provided with an oil-supply pipe while the last in the series is provided with a centrally-located discharge-orifice adapted to the mixing-chamber of a hydrocarbon-oil burner.

25 6. A hydrocarbon-oil burner comprising a detachable vaporizer located within the heat zone having an oil-supply pipe and a vapor-discharge orifice, said vaporizer being formed of a series of two or more retorts communicating with each other, each of said retorts being detachably secured to the body of the vaporizer, a mixing-tube communicating with the vaporizer and provided with air-inlet tubes, a series of burner-heads corresponding in number with the retorts and arranged about the mixing-chamber and communicating therewith each burner of the series being arranged directly below its corresponding retort and adapted to directly heat the same.

40 7. A hydrocarbon-oil burner comprising a detachable vaporizer provided with inlet and discharge connections, said vaporizer being formed of a series of two or more retorts arranged within the heat zone, each of said retorts being detachable from the body of the vaporizer, a hood mounted above the vaporizer, a curved baffle-plate suspended from said hood and arranged directly above the vaporizer, a centrally-located mixing-chamber communicating with the vaporizer having air-intake tubes secured to the hood, a series of burner-heads communicating with the mixing-chamber and provided with incandescent mantles.

55 8. A hydrocarbon-oil burner comprising a detachable vaporizer provided with inlet and discharge connections, said vaporizer being formed of a series of two or more retorts arranged within the heat zone, said retorts being detachable and communicating with each other, a hood and chimney mounted above the vaporizer having an air-chamber containing two or more air-inlet openings, a curved baffle-plate secured within the hood, a central mixing-chamber communicating with the vaporizer and having air-intake tubes secured to the hood, a series of burner-heads arranged

about the mixing-chamber and communicating therewith the same being provided with incandescent mantles, a needle-valve located in the mixing-chamber, and a globe suspended from the hood surrounding the burner.

70 9. A hydrocarbon-oil burner comprising a detachable vaporizer provided with an air-inlet pipe having an automatic check-valve in close proximity to the burner and a discharge-nozzle arranged centrally between a series of two or more retorts comprising the vaporizer, a mixing-chamber communicating with the vaporizer, the same being provided with air-inlet tubes, a series of burner-heads, surrounding and communicating with the mixing-chamber provided with incandescent mantles and a regulating-valve located in the mixing-chamber to regulate the flow of vapor from the vaporizer.

75 10. A hydrocarbon-oil burner comprising a detachable vaporizer formed of a series of two or more retorts, the vaporizer being provided with an oil-supply pipe, which has an automatic check-valve and a diaphragm-regulating valve in close proximity to the burner, a central mixing-chamber communicating with the vaporizer having air-intake tubes secured to a hood above the burner, a series of burner-heads surrounding the mixing-chamber and communicating therewith the same being provided with incandescent mantles adapted to heat the retorts, and an adjustable needle-valve in the mixing-chamber to regulate the flow of vapor from a nozzle in the vaporizer.

80 11. In a hydrocarbon-oil burner, the combination with two or more burners and an expansion-chamber, communicating therewith, of a vaporizer arranged to discharge into the expansion-chamber, the vaporizer consisting of a plurality of retorts corresponding in number to the burners and arranged respectively directly above the burners, said retorts communicating with each other, and each of which except the last of the series has a branch extending into the next retort in the series.

85 12. In a petroleum incandescent lamp, the combination with a hood, of two or more incandescent burners and an air-and-vapor-mixing chamber arranged directly below and suspended from the hood, and a vaporizer extending horizontally directly over and in vertical alinement with all of the burners and arranged at the top of the mixing-chamber, substantially as described.

90 13. In a petroleum incandescent lamp, the combination with the hood, of two or more burner-heads, an air-and-vapor-mixing chamber and a vaporizer, all suspended from the hood, the burner communicating with the mixing-tube at the lower end thereof and provided at the top with a multiplicity of small discharge-openings, the vaporizer extending horizontally directly over and in vertical alinement with all of the burners and arranged at the top of the mixing-chamber, substantially as described.

14. In a hydrocarbon-oil burner, the combi-

nation with a hood, of a burner, mixing-chamber and a laterally-extending vaporizer arranged below the hood, a chamber arranged above the hood having air-inlets and forming a passage for the air, and pipes for connecting the chamber above the hood with the mixing-chamber, and by means of which the mixing-chamber and burner are supported from said hood, the vaporizer being arranged at the top of and supported by the mixing-chamber, substantially as described.

15. In a petroleum incandescent lamp, the combination with the burners, of the mixing and expansion chamber arranged between and alongside of the burners, and a vaporizer located above the burners, the vaporizer comprising a series of two or more retorts communicating with each other each of which except the last of the series has a branch extending into the next retort of the series, the last retort of the series being provided with an orifice arranged centrally between the group and adapted to discharge into the mixing and expansion chamber.

25. 16. A petroleum incandescent lamp, comprising a hood, an expansion tube or chamber depending therefrom, having an opening for the ingress of air, a burner-head located above the lower end of the expansion-tube and communicating therewith, and provided at the top with a multiplicity of small discharge-openings; and a substantially horizontal vaporizer arranged above the burner-head and communicating with the top of the expansion-tube.

35. 17. A petroleum incandescent lamp comprising a hood, an expansion tube or chamber depending therefrom having an opening for the ingress of air, a burner-head located above the lower end of the expansion-tube and communicating therewith and provided with an incandescent mantle, and a horizontal vaporizing-tube arranged above the mantle and communicating with the expansion-tube.

45. 18. A vaporizer for hydrocarbon-oil burners comprising a series of two or more radially-disposed tubes or retorts, one of said retorts being provided with an oil-supply pipe, the last retort of the series being provided with a discharge-orifice located centrally between the retorts.

55. 19. A hydrocarbon-oil burner comprising a mixing-chamber having two or more burners arranged around the same and communicating therewith, a horizontal vaporizer above the burners having a series of two or more retorts disposed radially with respect to the mixing-chamber and corresponding in number to the burners, the last retort of the series being provided with an orifice located centrally between the retorts and arranged to discharge into the upper end of the mixing-chamber.

65. 20. A hydrocarbon-oil burner comprising, in combination, a hood, a plurality of burners, an upright mixing-tube between the burners and communicating therewith, a laterally-extending vaporizer arranged at the top of the

mixing-tube, the central portion of which communicates with the mixing-tube, while the radially-disposed outer tubes or retorts of 70 the vaporizer overhang the burners.

21. In a petroleum incandescent lamp, the combination with the hood, the burners, the mixing and expansion chamber arranged between and alongside of the burners, and a vaporizer located above the burners, the vaporizer comprising a series of two or more retorts communicating with each other each of which except the last of the series has a branch extending into the next retort of the series, the last retort of the series being provided with an orifice arranged centrally between the group and adapted to discharge into the mixing and expansion chamber, the said chamber, the burners and the vaporizer being suspended from the hood.

22. In a hydrocarbon-oil burner, the combination with a hood having the laterally-projecting annular flange, of two or more burner-heads, a vertically-extending air-and-vapor-mixing chamber arranged centrally below the hood, a horizontally-extending vaporizer arranged centrally at the top of the mixing-chamber, the vaporizer having a series of communicating retorts arranged directly over 95 the burner-heads and corresponding in number thereto, the last retort of the series having a discharge-orifice arranged centrally between the group of retorts, a chamber arranged above the annular flange of the hood, 100 there being an air-induction passage connecting the last-mentioned chamber with the mixing-chamber, the mixing-chamber, burner-heads and vaporizer being suspended from the hood, substantially as described. 105

23. In a hydrocarbon-oil burner, the combination with a hood having the centrally-disposed chimney and the laterally-projecting annular flange, of two or more burner-heads, an air-and-vapor-mixing chamber arranged between and communicating with the burners and directly beneath, and in substantial vertical alinement with the center of the chimney, and suspended from the hood, a horizontally-extending vaporizer arranged 115 at the top of and resting centrally upon the mixing-chamber, the vaporizer having a series of communicating retorts arranged directly over the burner-heads and corresponding in number thereto, the last retort of the 120 series having a discharge - orifice arranged centrally between the group of retorts, a chamber arranged above the annular flange of the hood, and air-induction tubes or pipes connecting the last-mentioned chamber with 125 the mixing - chamber, substantially as described.

Signed by me at Philadelphia, Pennsylvania, this 1st day of November, 1898.

DAVID S. WILLIAMS.
